Irving Grobstein, New York, N. Y.

Application December 2, 1940, Serial No. 96,996

Term of patent 3½ years

To all whom it may concern:

Be it known that I, Irving Grobstein, a citizen of the United States, residing in New York city, in the county of New York and State of New York, have invented a new, original, and ornamental Design for a Dress Ensemble, of which the following is a specification, reference being had to the accompanying drawings, forming part thereof.

Fig. 1 is a front view of a dress ensemble showing my new design.

Fig. 2 is a rear view of Fig. 1.

Fig. 3 is a front view of the dress member of the ensemble, and

Fig. 4 is the rear view thereof.

The characteristic feature of my design resides in the combination on the specific ensemble disclosed of the loose bolero jacket member having lace trimmed, embroidered cuffs in association with the specific dress member which has a matching lace trimmed, embroidered collar, all as shown.

I claim:

The ornamental design for a dress ensemble, substantially as shown and described.

IRVING GROBSTEIN.
